UNITED STATES PATENT OFFICE.

CLEMSON W. TAYLOR, OF PITTSBURG, PENNSYLVANIA.

ALARM-TRUNK.

Specification of Letters Patent No. 31,754, dated March 19, 1861.

To all whom it may concern:

Be it known that I, C. W. TAYLOR, of Pittsburgh, in the county of Allegheny and State of Pennsylvania, have invented a new and useful Alarm-Trunk; and I do hereby declare that the following is a full, clear, and exact description thereof, reference being had to the accompanying drawings, making a part of this specification, in which—

10 Figure 1 is a longitudinal section through the alarm trunk, taken in the vertical plane indicated by the red line x, x , in Fig. 2. Fig. 2 is a top view of the mechanism contained in the lid of the trunk as seen by a 15 section taken in the horizontal plane indicated by the red line y, y , Fig. 1.

Similar letters of reference indicate corresponding parts in both figures.

This invention is intended to guard 20 against the loss of trunks by being stolen from hotels, railroad stations, and other such places, and also to prevent thieves to some extent from purloining articles from a trunk should they be able to open the lid of the 25 same.

The invention consists in arranging, in a suitable place on the inside of the lid of a trunk, an ordinary clock alarm, having a bell which will give a full loud sound, and 30 in so combining with the hammer rod of the alarm a sliding rod and spring, as will be hereinafter described, that when the wheel-work of the alarm is wound up the hammer rod will be prevented from operating unless 35 the trunk, or the lid thereof is raised.

To enable those skilled in the art to make and use my invention, I will proceed to describe its construction and operation.

In the accompanying drawings, A. represents an ordinary traveling trunk, of 40 which B. is the lid or cover, and C. the tray in top of the body portion A. In the lid B. and near the front part of this lid the wheel-work for sounding the alarm is 45 arranged. This wheel-work is similar to that used for sounding the alarm in common clocks. D. is the coiled spring. a, its shaft, a', the toothed wheel which communicates motion from shaft a to the escapement 50 b and c. The verge c is secured to rocking shaft d, and to this shaft d the hammer rod e is secured carrying on its end a hammer e', which is made to strike the bell E.

f is a short rod which is secured to the 55 rocking shaft d, and which projects a suitable distance therefrom, to strike the end of

a straight rod F. The spring D. and escapement are all properly secured in a box formed of two plates G. G., and this box with the bell E. are firmly secured to the inside of board G', as represented in Figs. 1 and 2 of the drawings.

The board G' is secured across the front part of the lid B., and in a large trunk it will be very narrow and occupy a comparatively small space. Along the front edge of board G' extends the sliding rod F. which is allowed to have an endwise movement. From the bottom surface, and near one end of this rod F. projects two short pins g, g', 70 one of which (g) is caught and held by the hooked end of spring h, when the rod F. is pushed forward in the position shown by the black lines Fig. 1 and the trunk lid B. is shut. The spring h is forced up in the position above described by a perpendicular rod J. which passes down through a guard plate J' and projects below the lowest point of the bottom of the trunk. The rod F. being held in this forward position its end comes in contact with the rod f, and prevents the hammer e' from operating. The pin g' on rod F. catches against the edge of a hole i, through which the hooked end of spring h, passes when the alarm works are wound up, and 80 retains the rod F. in the desired position until the trunk lid is shut, then the upper end of rod J forces the spring h up, releases the pin g, and allows the rod F. to move the rod f until the spring h catches pin g', where 90 the parts are retained by spring h until this spring is released from rod J. either by raising the trunk so as to allow rod J. to be depressed, or by lifting the lid of the trunk and thus releasing the spring from the rod J. 95 When the pin g' is released from spring h by either of the methods described, the rod f forces the rod F. back, as represented in red lines Figs. 1 and 2, sufficiently far to allow the hammer e' to vibrate and strike the bell E. 100 The lower end of the perpendicular rod J projecting from the bottom of the trunk may have a metal ferrule on it to prevent it from wearing off; and this rod J. should be allowed to have a free endwise movement in its guard J' so that the spring h will force it downward when the trunk is raised.

The forward end of sliding rod F. should be allowed to have an upward play sufficiently far to clear the end of pin g from the 110 board G' when the spring h is forced against this rod F. Then when the spring h releases

rod F. this rod is moved backward and allows the alarm to sound.

The operation of the invention is as follows: The lid of the trunk is raised, the hand is put behind the board G', and the rod F. is pushed forward until the pin g falls into hole i and catches on the edge of this hole. The pin g now retains the rod F. in this position, and this rod F. will now press 10 against arm f and prevent the hammer rod from vibrating. The spring D. is now wound up by a common clock key and the lid of the trunk closed and locked. In shutting the lid of the trunk the rod J. forces the hooked 15 end of spring h upward and releases the pin g from the edge of hole i, but the pin g' catches against spring h and prevents the rod F. from being forced farther back, this rod F. still prevents the alarm from sound-

ing. Now it will be seen that should the 20 trunk be lifted up the spring h will release the rod F. and the alarm will sound, or if the lid of the trunk be raised the spring h will release the rod F. and the alarm will be sounded.

25

Having thus described my invention, what I claim as new and desire to secure by Letters Patent; is:—

The clock alarm, in combination with the lever F, board G', rod f, spring h, and rod J, 30 the whole being constructed and operated, substantially in the manner and for the purpose set forth.

CLEMSON W. TAYLOR.
